UNITED STATES PATENT OFFICE.

JOHN A. ROSSI, OF NORTH YAKIMA, WASHINGTON.

TENT ATTACHMENT.

1,213,022.

Specification of Letters Patent. Patented Jan. 16, 1917.

Application filed June 20, 1916. Serial No. 104,787.

To all whom it may concern:

Be it known that I, JOHN A. ROSSI, a citizen of the United States, residing at North Yakima, in the county of Yakima and State 5 of Washington, have invented new and useful Improvements in Tent Attachments, of which the following is a specification.

This invention relates to an attachment for tents which may be applied thereto in 10 such a manner as to surround the stove pipe opening therein and serve as a protector for the tent.

The primary object of the invention is to provide an attachment of the class described 15 which when applied to a tent in such a manner as to surround the stove pipe opening therein prevents the tent from becoming damaged when the stove pipe is in a heated condition, said attachment having the parts 20 thereof so arranged and constructed that the attachment may be used as a ventilator for the tent when desired.

With these and other objects in view, the invention resides in the novel combination 25 and arrangement of parts, which will be hereinafter described and particularly pointed out in the claim.

The preferred embodiment of the invention has been illustrated in the accompanying 30 drawing, although no restriction is necessarily made to the precise details of construction therein shown, as changes, alterations, and modifications within the scope of the claim may be resorted to when desired.

Like characters of reference denote corresponding parts throughout the several views in the drawing, in which:

Figure 1 is a top plan view of a portion of a tent showing the attachment applied thereto. Fig. 2 is a transverse sectional view on the line 2—2 of Fig. 1. Fig. 3 is a view similar to Fig. 1 showing the cover plate removed from the attachment. Fig. 4 is a view looking at the under-side of the attachment and showing the same applied to a tent and used as a window. Fig. 5 is a transverse sectional view on the line 5—5 of Fig. 4 showing the attachment used as a ventilator. Fig. 6 is a plan view of one of the clamping 45 members removed from the attachment.

Referring now to the drawing in detail, the numeral 1 designates a portion of a tent which may be of any well known type having an opening 2 therein through which a 50 stove pipe 3 may be passed.

The improved attachment 4 comprises a

body 5 which is a flat disk-shape plate 8 and is provided on its marginal edge with a circumferentially extending bead 9 and has formed therein an eccentrically arranged and elliptical shaped opening 10 surrounding the peripheral edge of which is an upstanding collar 11 formed integral with the plate 8 and flared at diametrically opposite points, so that when the body 5 is in an inclined position, the collar 11 is in substantially a vertical plane.

Fastening members 12 which are in U-form to provide each fastening member with arms 13 and 14 are arranged at diametrically opposite points on the under-side of the 70 plate 8, the respective arms on each fastening member 12 passing through openings 15 in the plate 8 with the arms 14 on each fastening member positioned adjacent a flared portion on the collar 11.

A disk or plate 16 of protective material such as asbestos, or the like, is positioned upon the upper face of the plate 8 and covers the outer face of the collar 11.

The plate 8 is provided upon its inner 80 face at diametrically opposite points between the fastening members 12 and adjacent the collar 11 with an eye 17, the shank 18 of which is threaded and passes through an opening 19 in the plate 8 to receive a thumb-nut 20.

The upper face of the plate 8 has mounted thereon a pair of clamping members 21 and 22 arranged circumferentially about the collar 11 with each clamping member formed 90 from a strand of wire convoluted throughout its length, as at 23, with the convolutions decreasing in length toward the respective ends of the clamping members from a point intermediate said ends. Each clamping 95 member is received between its ends in an eye 17 and has its respective terminals provided with eyes 23' in which are received the arms 14 on the fastening members 12, said arms being threaded to receive nuts, or the like, which enable the arms 14 to co-act with the eyes 17 in securing the clamping members to the plate 8.

A cover plate 24 which corresponds in shape to the plate 8 has its outer marginal 105 edge beaded, as at 25, and it is provided with an eccentrically arranged and elliptical opening 26 adapted to register with the opening 10 in the plate 8 and is surrounded by an upstanding flange 27, the free edge of 110 which is rolled, as at 28, to provide a groove

29 in which the free edge of the collar 11 is adapted to seat.

The cover plate 24 is bulged between the flange 27 and the bead on the rim thereof to 5 over-lie the clamping members 21 and 22 so that, when the cover plate over-lies these members, the beaded marginal edges of said plates will be in contacting relation.

The cover plate 24 has formed therein at 10 diametrically opposite points openings 29 through which extend the arms 13 and the fastening members 12, said arms being threaded to receive thumb-screws by means of which the cover plate 24 may be removably connected to the plate 8.

A sash frame 30 has mounted therein a transparent panel 31 and has formed integral therewith fingers 32 which, when the sash frame is inserted in the opening 10 in 20 the plate 8 may be interposed in the groove 29 in the flange 27 and in this manner secure the sash frame within the opening in the attachment which normally receives the stove pipe.

25 A frame 33 similar in construction to the frame 30 has mounted therein screen fabric 34, said frame having attaching fingers 35 connected therewith and adapted to be positioned within the groove 29 in the flange 27 30 to close the opening in the attachment when the same is used as a ventilator.

When it is desired to connect the attachment with a tent, the cover plate 24 is removed from the plate 8 and the plate 8 arranged interiorly of the tent with the collar 11 received in the stove pipe opening therein so that the portion of the tent adjacent said opening may be arranged between the clamping members and plate 8. The cover plate 24 may now be arranged to over-lie 40 the clamping members and plate 8 and may be connected with said plate by the arms 13.

With reference to Fig. 3 in the drawing,

it will be noted that the convoluted portions of the clamping members not only 45 serve to clamp the tent to the plate 8 but space the cover plate a sufficient distance from the plate 8 to enable the portion of the tent positioned between the plate 8 and the cover plate to remain cool when the stove 50 pipe passing through the opening in the attachment is in a heated condition and to also enable this portion of the tent to dry when in a wet condition.

When the pipe has been removed from 55 the attachment, the sash frame may be inserted within the opening in the attachment and the attachment used as a window or if found desirable, the screen frame may be connected with the attachment and insects 60 prevented from entering the tent while the perfect ventilation of the same is insured through the use of the attachment.

From the foregoing description, taken in connection with the accompanying drawings, it is at once apparent that an attachment 65 for a tent has been provided which not only prevents the tent being damaged by an over-heated stove pipe but enables the tent to be ventilated at all times.

Having thus described the invention, what is claimed as new, is:

An attachment for a tent comprising a plate forming a body and having an opening therein, a collar surrounding said opening, convoluted clamping members connected with the plate and arranged circumferentially about said opening, a cover plate for connection with the first mentioned plate and having a flange for connection with the 75 collar, a frame for disposition within said opening, and fingers on said frame to be received between the collar and flange.

In testimony whereof I affix my signature.

JOHN A. ROSSI.
